PACKAGING AND DISPLAYING DEVICE

Manuel Essman, New York, N. Y.

Application April 24, 1948, Serial No. 23,111

4 Claims. (Cl. 206—80)

1

This invention relates to a novel device for packaging and displaying neckties and has as its primary object the provision of a device which will retain neckties in clean and neat condition while simultaneously allowing the neckties to be viewed instantaneously for selection.

Neckties are generally displayed in retail establishments either hanging from upright tie racks, or stacked within a display counter, or even laid out loosely on a counter or table. Repeated handling of the neckties by salesmen and prospective purchasers frequently results in soiling and requires constant readjustment of the neckties to preserve a neat and attractive appearance.

The device of the present invention, on the other hand, allows neckties to be neatly displayed and inspected by prospective purchasers without requiring the harmful and undesirable handling and fingering which has been inevitable heretofore.

Another object of the invention is the provision of a device of the character described for displaying and retaining neckties which may be fabricated inexpensively, which may be used effectively in the home and during travel and which conserves space.

The foregoing objects as well as additional objects and advantages of the invention will be readily apparent in the course of the following detailed description taken in connection with the accompanying drawing which illustrates a preferred embodiment, and wherein:

Fig. 1 is a plan view of a mounting element upon which the necktie may be folded.

Fig. 2 illustrates the initial step of adjusting the necktie on the mounting element.

Fig. 3 illustrates a subsequent step in the folding of the necktie about the mounting element.

Fig. 4 illustrates the necktie completely folded about the mounting element, the folded necktie and mounting element being removably contained within a transparent wrapping or envelope.

Mounting element 10 may be cut from a substantially rectangular blank of cardboard, fiberboard or any other suitable material. In the preferred embodiment of the invention, mounting element or board 10 has parallel sides and is formed along its top edge and adjacent one of its sides with a spacing tab 11 defining a mounting edge 12 on one side thereof for the reception of the folded end of necktie 13, as clearly shown in the drawing. A cutout 14 is provided so that the lower fold 13a of the necktie may be passed over the front face of the mounting element 10 to

2

immediately underlie outer fold 13b, as illustrated in Fig. 2.

Upper fold 13b and lower fold 13a of the necktie are brought downwardly over the front face of mounting element 10 to be received within bottom recess 14 formed in the bottom edge thereof. Recess 14 is preferably further provided with a medial depression 14a for the reception of lower fold 13a of the necktie and terminates laterally in a notch 15 for retaining the edge of upper fold 13b, as clearly shown in Figs. 3 and 4.

Upper fold 13b and lower fold 13a are next passed upwardly over the back of mounting element 10 to be received within top recess 16 formed in the top edge of said mounting element on that side of spacing tab 11 opposite mounting edge 12. Top recess 16 is preferably provided with a medial depression 16a for the reception of lower fold 13a of the necktie. An integral top edge tab 17 defines a lateral notch 18 for retaining the edge of upper fold 13b. The mounting of the necktie on element 10 is completed by passing the free ends of upper fold 13b and lower fold 13a downwardly across the front of said element, as shown in Fig. 4.

After having been adjusted on mounting element 10 in the manner indicated, necktie 13 and said mounting element are inserted within a wrapper or envelope 19 of transparent material. Transparent envelope 19 may be formed from regenerated cellulose, cellulose acetate or the like. It will be noted that the top edge 17a of tab 17 and the top edge 11a of spacing tab 11 preferably lie in the same plane in order to properly align mounting element 10 within transparent envelope 19. Also the axis of bottom tie-receiving recess 14 and top tie-receiving recess 16 are angularly inclined in opposite direction in order to fold the tie over the entire compass of mounting element 10.

Mounting element 10 is so proportioned with respect to transparent envelope 19 as to present an integral finger-hold projection 20 for readily withdrawing said mounting element when the necktie is to be removed therefrom.

By the use of the novel device of the present invention it is apparent that ties may be individually mounted and displayed in their transparent envelopes for inspection by the prospective purchaser. The pattern and color of each tie may be viewed apart from the remaining ties in a particular collection and a neat, clean and attractive appearance preserved by eliminating excessive and repeated fingering. Upon being selected by

the purchaser the packaged tie requires no additional wrapping or handling.

The device is adapted for a variety of uses in addition to its indicated use as a display and packaging device for retail establishments. For example, by slight modification, a plurality of such devices may be mounted within a binder or portfolio which may be convenient carried in a handbag during travel or which may be placed within a drawer or upon a closet shelf to relieve congestion and conserve space. This may be accomplished by the simple expedient of affixing a perforated backing strip (not shown) to the closed end of the transparent envelope of the device after which a number of such envelopes may be readily mounted in a looseleaf binder or the like to be easily turned for the selection of a particular tie or ties.

The protective transparent envelope 19 is substantially dustproof and, in combination with the mounting element 10, will preserve the necktie against the wrinkling, limpness, loss of shape and general abuse attendant upon hanging from conventional tie racks.

Since certain modifications may be made in the device of the present invention without departing from the scope thereof, it is intended that all matter contained in the foregoing description and shown in the accompanying drawing be interpreted merely as illustrative and not in a limiting sense.

What is claimed is:

1. A device for displaying and retaining neckties comprising a flat mounting element formed from a single blank, said mounting element having a spacing tab formed in the upper edge thereof and defining a mounting edge for the reception thereagainst of the folded end of a necktie and an upper tie-receiving recess, said upper recess having a medially depressed portion for retaining the lower fold of the necktie, a cutout portion spaced below said mounting edge for passing the lower fold of the necktie downwardly across the front of said mounting element to underlie the upper fold of the necktie, a lower necktie-receiving recess formed in the bottom edge of said mounting element, said lower recess having a medially depressed portion for retaining the lower fold of the necktie, transparent protective means within which said mounting element is removably insertable, said upper and lower tie-receiving recesses being angularly inclined in opposite directions, whereby to fold the necktie over the entire compass of the mounting element.

2. A device for displaying and retaining neckties comprising a flat mounting element formed from a single blank having a pair of parallel sides, said mounting element having a spacing tab formed in the upper edge thereof and defining a mounting edge for the reception thereagainst of the folded end of a necktie and an upper necktie-receiving recess, a cutout portion spaced below said mounting edge for passing the lower fold of the necktie downwardly across the front of the mounting element to underlie the upper fold of the necktie, a lower necktie-receiving recess formed in the bottom edge of said mounting element, said upper and lower tie-receiving recesses being angularly inclined in opposite directions, whereby to fold the necktie over the entire compass of the mounting element, transparent protective means enclosing said mounting element, the upper edge of said mounting element having an edge tab adjacent

upper necktie-receiving recess and substantially on the same level as said spacing tab for preventing contact between the necktie and the upper edge of said protective means.

3. A device for displaying and retaining neckties comprising a flat mounting element formed from a single blank having a pair of parallel sides, said mounting element having a spacing tab formed in the upper edge thereof and defining a mounting edge for the reception thereagainst of the folded end of a necktie and an upper necktie-receiving recess, a cutout portion spaced below said mounting edge for passing the lower fold of the necktie downwardly across the front of said mounting element to underlie the upper fold of the necktie, a lower necktie-receiving recess formed in the bottom edge of said mounting element, said upper and lower tie-receiving recesses being angularly inclined in opposite directions, whereby to fold the necktie over the entire compass of the mounting, transparent protective means enclosing said mounting element, the upper edge of said mounting element having an edge tab adjacent said upper necktie-receiving recess and substantially on the same level as said spacing tab for preventing contact between the necktie and the upper edge of said protective means, said edge tab having an inner laterally extending notch communicating with said upper necktie-receiving recess for retaining a respective edge portion of the necktie, and said lower necktie-receiving recess having a lateral notch for retaining a respective edge portion of the necktie.

4. A device for displaying and retaining neckties comprising a flat mounting element formed from a single blank and having parallel sides, said mounting element having a spacing tab formed in the upper edge thereof and defining a mounting edge for the reception thereagainst of the folded end of a necktie and an upper necktie receiving recess, said upper recess having a medially depressed portion for retaining the lower fold of the necktie, an integral edge tab defining a terminal laterally extending notch in said upper recess for retaining the edge portion of a necktie, a cutout portion spaced below said mounting edge for passing the lower fold of the necktie downwardly across the front of said mounting element to underlie the upper fold of the necktie, a lower necktie receiving recess formed in the bottom edge of said mounting element, said lower recess having a medially depressed portion for retaining the lower fold of the necktie, said lower recess having a lateral notch for retaining the respective edge portion of the necktie, the axis of said upper and lower tie receiving recesses being angularly inclined in opposite directions, whereby to fold the necktie over the entire compass of the mounting element, and a transparent envelope within which said mounting element is removably insertable.
